UNITED STATES PATENT OFFICE.

HOWARD DE WALDEN AND HANS KNUDSEN, OF LONDON, ENGLAND.

AERIAL VESSEL.

SPECIFICATION forming part of Letters Patent No. 769,034, dated August 30, 1904.

Application filed Aug. 3, 1903. Serial No. 150,967. (No model.)

To all whom it may concern:

Be it known that we, HOWARD DE WALDEN, a subject of the King of Great Britain, residing at Seaford House, Belgrave Square, and 5 HANS KNUDSEN, engineer, a citizen of the United States of America, residing at 29^A Gillingham street, London, England, have invented certain new and useful Improvements Relating to Mechanically-Propelled Aerial 10 Vehicles, of which the following is a specification.

This invention has reference to mechanically-propelled aerial vehicles.

Up to the present it has been usual to construct aerial vehicles in such a way that the car carrying the propelling machinery is only a short distance below the inflatable or buoyant portion.

Now according to this invention we provide for the suspension of the car and machinery at a very considerable distance from the buoyant portion, so that the weight is concentrated at a considerable distance below the point of suspension. In this way a great 25 range of stability is attained. The lifting or flying power is obtained not by buoyancy, but by aeroplanes, the buoyant portion being only employed to neutralize the weight and not to effect the actual lifting operation. The steering 30 is performed by means of specially-constructed rudders, which are arranged so that they will expand and act as parachutes in the event of the vehicle descending too rapidly. Other parachutes may also be provided in convenient positions for checking the speed of 35 the descent.

The vehicle is propelled by means of screws.

In order that our said invention may be clearly understood and readily carried into 40 effect, we will proceed to describe the same more fully with reference to the accompanying drawings, in which—

Figure 1 is an end view, Fig. 2 a side view, and Fig. 3 a plan, of one construction of our 45 improved aerial vehicle. Fig. 4 is an under side view showing one of the rudders in its expanded condition. Fig. 5 is a plan, Fig. 6 a front edge view, and Fig. 7 a rear edge view, of one of the aeroplanes.

a is the main frame or skeleton structure of 50 the vehicle, which is formed of light steel tubes and is of more or less rectangular form, its greatest length being in a vertical direction.

b is the car, which the frame *a* serves to connect with the buoyant upper part of the vehicle at a relatively considerable distance therefrom, whereby the center of gravity of the vehicle is situated far below the buoyant portion, so as to offer resistance to any tendency of the vehicle to move out of the vertical. 55

c c are gas vessels or envelopes which constitute the said buoyant or supporting portion and which, as already stated, although not of sufficient capacity to raise the vehicle from 60 the ground, are large enough to practically neutralize the weight of the said vehicle. These gas vessels contain hydrogen or other appropriate buoyant gas, the buoyant effect being made sufficient to keep the structure 65 erect when resting on the ground.

d d are the aeroplanes, which constitute two louver-like groups or sets, one situated at the front and the other at the rear of the structure. Each aeroplane is composed of a frame having 70 its front edge *d'* straight and its rear edge *d''* bent to the shape of an obtuse angle. (See Figs. 5, 6, and 7.) Each frame is covered with light flexible material, such as oiled silk or gold-beaters' skin. As the vehicle is propelled the pressure of the air causes this material to belly or curve upward, so that the 75 said aeroplanes act as aerocurves, which have been found to possess much greater lifting power than aeroplanes. The frames of the 80 aeroplanes are connected pivotally at *d*³ to the framework of the vehicle, so as to be capable of simultaneous movement for adjusting the angle of the planes. For this purpose the aeroplanes of each set are at their inner edges 85 pivotally connected to rods *d*⁴, which are connected by a swing-bar *d*⁵, pivoted at *d*⁶, to the frame of the structure. The inclination of this bar, and therefore of the aeroplanes, is controlled by a hand-wheel *d*⁹ through the medium of a 90 chain *d*⁷ and a chain-wheel *d*⁸.

e e are the rudders, which are hinged at *e'* and are formed of flexible material. They are

mounted on the vertical frames e^2 at each end of the vehicle. The flexible material consists of two thicknesses, which are unconnected together at the bottom, so that should the vehicle descend too rapidly the air will find its way between the said two thicknesses of the material and cause them to open or expand after the manner of a parachute. For this purpose the lower edges of the two thicknesses of flexible material are carried by hinged bars $e^3 e^4$, and the ends of the two outer hinged bars are connected with a sleeve e^4 , which is capable of sliding on the lower horizontal member e^5 of the framework of the rudder. So long as the vehicle continues an even course the said sleeve maintains its position near the end of the lower horizontal member e^5 ; but in the event of the vehicle descending too quickly the said sleeve will slide inwardly under the pressure of the air entering the open lower end of the rudder, and thereby cause the latter to automatically open and operate as a parachute. The position of the rudders for the purpose of steering is controlled by any convenient means—such, for instance, as a cord e^6 , passing over a pulley e^7 , operated by a steering-wheel e^8 . f is another parachute of umbrella or other appropriate formation, which may be normally held in a contracted condition by cords or ropes under the control of the occupants of the car, so that they can in cases of emergency render this parachute capable of opening if it should be found that the rudder-parachutes are for any reason ineffectual in properly checking the descent of the vehicle.

$g g$ are screw-propellers for driving the vehicle. These are arranged in two pairs at the front and rear of the vehicle, one screw of each pair being at the top and the other at the bottom of that portion of the frame in which the aeroplanes are situated. These propellers are geared together and are driven by means of cords or bands g' and pulleys g^2 from a pair of smaller pulleys g^3 , each driven by a separate motor or turbine g^4 . These motors are arranged so that they can be driven either separately or simultaneously.

h is an expanding fin arranged beneath the car. In the example shown the said fin consists of a sheet of flexible material provided with radial ribs h' . This fin when in its expanded state will offer a resistance to any undesirable lateral movement of the car, so as to prevent or check the swinging of the latter.

$i i$ are rubber-covered wheels, of which there may be four, for supporting the car when on the ground.

What we claim, and desire to secure by Letters Patent of the United States, is—

1. In an aerial vehicle, the combination with a rectangular skeleton frame, having its greatest length in a vertical direction, of a car connected with the lower end of said skeleton frame, frames arranged in two vertical series or groups at the fore and aft of said skeleton frame and covered with flexible fabric to form aeroplanes, the front edge of each of said frames being straight and the rear edge bent to an obtuse angle, hinge connections at the straight edges of said frames, lever mechanism for simultaneously setting said hinged frames to the desired vertical angle from the car, means for propelling the vehicle, and means for steering the same, substantially as described.

2. In an aerial vehicle, the combination with a rectangular skeleton frame having its greatest length in a vertical direction of a car connected with the lower end of said skeleton frame, frames arranged in two vertical series or groups at the fore and aft of the skeleton frame and covered with flexible fabric to form aeroplanes, the front edge of each of said hinged frames being straight and the rear edge bent to an obtuse angle, hinge connections at the straight edges of said frames, sliding rods to which the hinged frames are connected, a rocking bar connecting together the lower ends of said sliding rods, means for actuating said rocking bar from the car, means for propelling the vehicle, and means for steering the same, substantially as described.

3. In an aerial vehicle, the combination with a rectangular skeleton frame having its greatest length in a vertical direction, of a car connected with the lower end of said skeleton frame, adjustable aeroplanes arranged in two series or groups at the fore and aft of the said skeleton frame, means for adjusting said series or groups of aeroplanes from the car, means for propelling the vehicle, rudders at the fore and aft of said skeleton frame, means for actuating them from the car, and means whereby said rudders will expand laterally and act as parachutes in the event of the vehicle tending to descend too quickly, substantially as described.

In testimony whereof we have hereunto set our hands, in presence of two subscribing witnesses, this 23d day of March, 1903.

HOWARD DE WALDEN.
HANS KNUDSEN.
